UNITED STATES PATENT OFFICE

2,644,474

MEANS FOR FLUSHING OUTBOARD MOTORS

Frank M. Houchin, Miami, Fla., assignor of one-half to William C. Lauth, Miami, Fla.

Application March 16, 1951, Serial No. 215,907

2 Claims. (Cl. 134—166)

1

The present invention relates to an improved means for effectively flushing and cleansing the coolant jacket of outboard marine engines of the detachable type and the obvious purpose of the invention is to enable one to periodically bring the engine ashore and flush the stated jacket so that same may be maintained in a satisfactory condition for efficient operation at all times.

It is a matter of common knowledge that outboard motors which are used in bodies of salt water are subject to corrosion and rusting. It is highly important, therefore, to flush the coolant circulating jacket from time to time and to, in this manner, prevent hampered circulation and clogging.

It is customary practice to detach the outboard motor from the boat or other craft and to submerge the same in fresh water contained in a suitably sized drum or barrel. During the flushing operation, it is necessary to operate the motor, which brings the customary pump into play, and circulates the fresh water through the cooling system and expels the salt water or coolant right back into the fresh water, as is well known. The fresh water is thus partly charged with salt water and is unsatisfactory as a good flushing and cleansing fluid.

There has long existed a recognized need for a more satisfactory means for flushing and cleansing outboard motors, particularly the coolant circulating jacket. The present invention, therefore, has to do with practical and acceptable simple and efficient structural devices in which manufacturers and users will find their essential requirements and needs fully met, contained and effectually available.

When an outboard motor is in use on a craft, the water for cooling purposes is provided through the action of a vari-volume impeller or equivalent type pump which, as a general rule, is operated from the motor drive shaft. The pump forces the water through a vertical delivery pipe or the like directly into the water intake at the bottom of the water jacket provided in the motor or cylinder block. The water is circulated through the jacket and empties through a discharge opening also in the bottom of the jacket, this by way of an existing elbow, passes through the elbow and then through a suitably curved length of tubing from which it is discharged into the depending drive shaft housing, which latter serves as the exhaust housing. The discharge water is expelled with the exhaust gases by way of the customary underwater exhaust outlet carried by said housing.

Briefly, the herein described invention has to do with forcibly expelling used coolant from the coolant circulating jacket of the stated motor block, this being done with the motor out of the water and, of course, not running. The procedure consists in directly injecting fresh water or an equivalent cleansing fluid, which is under

pressure from an external source. The flushing water is introduced directly into the discharge end of the coolant jacket, is caused to flow in a reverse direction and leaves or discharges from the jacket, with the salt water coolant, by way of the coolant intake port, openings in the pump housing, and the pipe or line which connects said housing with the usual coolant inlet or port.

It is well known that while an outboard motor is running, that portion of the discharged cooling water that enters the exhaust housing near the exhaust cylinder ports of the motor is kept from entering such exhaust ports by the pressure of the burnt gases discharged from said exhaust ports; is converted into a cooling steam which lowers the temperature of the burnt exhaust gases, thereby contracting the burnt gases and allowing them to be discharged through the underwater exhaust outlet with less back pressure on the exhaust system, at the same time, lowering the temperature of all metals which the exhaust gases contact.

More specifically, the function of the device is to flush out brine solution from the cooling system after salt water operation, by by-passing all openings such as the water outlet tube or opening that normally discharges cooling water, in whole or in part, into exhaust pipe, exhaust tubes or drive shaft housing near exhaust ports, pistons, piston rings and cylinder walls of the engine.

Employment of the means herein disclosed eliminates the necessity of using a drum or barrel filled with fresh water, does away with the dilution of the fresh water with salt water, obviates the necessity of operating the motor while flushing, saves time, eliminates noise, is altogether a highly efficient and an economical approach to the proper procedure of amply and aptly flushing the coolant circulation jacket of outboard motors.

Other objects and advantages will become more readily apparent from the following description and the accompanying sheet of illustrative drawings.

In the accompanying sheet of drawings, wherein like numerals are employed to designate like parts throughout the views:

Figure 1 is a side elevational view, with portions broken away and shown in section, of a conventional-type outboard motor of the detachable type showing the invention;

Figure 2 is an enlarged view in section and elevation showing the assembly, the T-coupling, detachable nozzle and means to accommodate the hose and discharge tubing, respectively;

Figure 3 is an elevational view, parts being in section of the T-coupling which is substituted for the usual elbow found on conventional outboard motors; and

Figure 4 is a cross-section on the horizontal line 4—4 of Figure 2, looking in the direction of the arrows.

Reference being had to Figure 1, the motor proper is denoted generally by the reference character 6 and includes the cylinder block 8, one of the pistons 10 and the water jacket 12. The numeral 14 denotes the vertical or depending hollow housing which encases the drive shaft and other parts. This housing includes the usual underwater exhaust branch 16. The drive shaft is denoted at 18 and intermeshing gears at 20 and 22, these driving the power take-off shaft 24 which operates the exteriorly disposed propeller. The pump housing is denoted at 28 and the rotor or impeller, as the case may be, at 30. Attached to and rising vertically from the pump housing is the delivery pipe or line 32 which ascends water under pressure into the bottom of the jacket 12 at the usual intake port or inlet (not shown). The numeral 34 designates a hook or similar clamp which suspends the over-all outboard motor on a boat or other craft. Under ordinary circumstances an elbow (not shown) is attached to the discharge end 36 of the circulating jacket and a length of tubing 38 is attached to the elbow and delivers the exhausted coolant into the exhaust housing where, as before stated, it is discharged through the outlet 16.

To pave the way for the utilization of the mechanical means which is herein involved and employed, the customary elbow (not shown) is detached from the coolant discharge port 36 and the special adapter-type fitting 40 is substituted therefor. This fitting as shown in Figures 2 and 3 is a T construction. The upper vertical branch 42 is externally screw-threaded at 44 and is screwed into the discharge port at the point 36 as shown in Figure 1. This branch 42 is also internally screw-threaded, as at 46. The lower vertical branch 48 is screw-threaded, as at 50, and this serves to accommodate an insertable and removable screw-plug 52. The latter has a screw-driver kerf 54 for convenience of removal and insertion. The intermediate or horizontal branch 56 has a screw-threaded nipple 58 to which the aforementioned discharge tubing 38 is connected. Thus, with the plug 52 in place, the fitting 40 functions as usual.

The second unit or part takes the form of an injector nozzle which is denoted, as a unit, by the numeral 60. This is an elongated tube which, as shown in Figure 2, has a reduced neck 62 which is externally screw-threaded and is screwed into the threads 46. The intermediate portion of the nozzle extends downwardly through and beyond the screw-threaded opening 50 where it is provided with a tool nut 64. It is also provided below the nut with a screw-threaded end or nipple 66 to accommodate an adapter 68 carrying a female-type swivelly mounted hose coupling 70. An ordinary garden hose 71 is threadedly connected, in an obvious manner, with the coupling 70.

With the parts as assembled in Figures 1 and 2 and with the garden hose attached, it will be obvious that the flush water, under city or other pressure, is introduced directly into the water jacket by way of the nozzle 60 which, it will be noted, by-passes the branch 56. The flushing operation is performed after the outboard motor has been removed from the boat, or as a unit, both may have been removed from the water. It is not necessary, or advantageous, to have the motor running during the operation, since the motor's pump would then be working against the water pressure applied in the flushing operation. This device was designed primarily for the 5 H. P.

series of Johnson outboard motors, whether using the propeller shaft driven type rubber rotor pump, or the drive shaft driven rubber impeller type pump. However, the device could as well be utilized on any make of outboard engine with the same beneficial results, where the said outboard marine engine discharged any portion of the cooling water into a combination drive shaft housing and exhaust housing or into a separate exhaust housing, since my chief claim is that by the use of this device, I by-pass or close off, any opening leading into the exhaust housing that normally discharges a portion of the cooling water therein, in order that the flushing operation may be safely accomplished by directing and confining all such flushing water to the jacket of the outboard motor in such a manner to assure that no flushing water under pressure during the flushing operation could enter the exhaust housing and enter motor exhaust cylinder ports thereby causing rust of cylinder wall, piston rings or other internal, highly finished motor parts.

It is thought that persons skilled in the art to which the invention relates will be able to obtain a clear understanding of the invention after considering the description in connection with the drawings. Therefore, a more lengthy description is regarded as unnecessary.

30 Minor changes in shape, size and arrangement of details coming within the field of invention claimed may be resorted to in actual practice, if desired.

Having described the invention, what is claimed as new is:

1. In combination, a T-coupling having all of its branches open with one branch being both internally and externally screw-threaded, the opposite branch being internally screw-threaded to accommodate a screw-plug, the remaining branch being constructed to accommodate a coolant discharge tube, an injector nozzle telescopically fitting in and through said first named branches and having one end screw-threaded and screwed into said first named branch, said nozzle bridging and blocking off said remaining branch and extending through and beyond the second named branch and being provided with means whereby a garden hose may be attached thereto.

50 2. The structure defined in claim 1, wherein said means is a detachable union provided with a swivelly attached hose coupling.

FRANK M. HOUCHIN.
